SASH MOUNTING

Filed June 7, 1928

UNITED STATES PATENT OFFICE

JAMES ADAMS STEWART, OF OAKLAND, CALIFORNIA, ASSIGNOR TO MANAGEMENT AND FINANCE CORPORATION OF CALIFORNIA, OF SAN FRANCISCO, CALIFORNIA, A CORPORATION OF CALIFORNIA

SASH MOUNTING

Application filed June 7, 1928. Serial No. 283,547.

The invention relates to a mounting for a sash of the swinging type.

An object of the invention is to provide an improved mounting for a swingable sash having a weather flange engageable against the outer side of a window casing, said mounting having no parts thereof protrude from the window opening or casing.

Another object of the invention is to provide a mounting of the class described which is automatically operative to effect a resilient engagement of the weather flange with the casing when the sash is in closed position.

A further object of the invention is to provide a mounting means of the class described in which provision is made for the adjustment of the sash with respect to the mounting whereby the resilient engagement of the weather flange with the casing may be assured.

The invention possesses other objects and features of advantage, some of which, with the foregoing, will be set forth in the following description of the preferred form of the invention which is illustrated in the drawings accompanying and forming part of the specification. It is to be understood, however, that variations in the showing made by the said drawings and description may be adopted within the scope of the invention as set forth in the claims.

Referring to said drawings,

Figure 1 is a plan view of a sash mounted in a window frame by means embodying one form of the invention, the sash being in closed position and portions of the structure being broken away as at lines 1-1 and 1'-1' in Figure 7.

Figure 2 is a plan view of the structure of Figure 1, the top member of the frame being removed and the sash being in an extended position, the view being taken at the line 2-2 in Figure 1.

Figure 3 is an enlarged fragmentary plan sectional view showing the sash in a position intermediate to those shown in Figures 1 and 2.

Figures 4 and 5 are enlarged perspective views of shoes having differently formed

members for attaching the shoe to the sash pivoted thereto.

Figure 6 is a fragmentary corner face view of the structure shown in Figure 1.

Figure 7 is an edge sectional view of the frame and sash, taken on the line 7-7 in Figure 1.

Figure 8 is an enlarged perspective fragmentary view showing a modification of the structure shown in Figures 1 to 6.

As particularly illustrated in Figures 1 to 6 of the drawings, the invention is applied in effecting a swinging mounting of a metal sash 14 in a metallic window frame 16. The frame 16 is here shown formed of members 17 of I-beam section having one flange 18 defining the front of the frame as a casing member therefor, with the webs 19 of the members cooperating with the front flanges 18 and the rear flanges 21 to define a channel 22 within the area of the frame. The sash 14, it is noted, is formed with stiles 23 of right-angled Z section, said stiles being fixed together in such relation that the webs 24 thereof define the pane receiving opening of the sash, and flanges 26 extend outwardly therefrom as lateral extensions at one face of the sash. The area defined by the outer edges of the sash flanges 26 exceeds that of the area defined within casing flanges 18 whereby, when the sash is disposed in closure relation in the window frame, the rear surfaces of the flanges 26 will engage flat against the outer faces of the casing members 18 of the frame. As particularly shown, the frame members 17 are integrally joined at their points of abutment to define an integral frame of fixed size, and the sash stiles 23 are similarly joined to provide a unitary sash structure.

In the present embodiment, the sash is pivotally mounted on and between upper and lower shoes 27 and 28 arranged for slideable movement along the upper and lower frame channels 22 in guideways 29 provided therein, the pivotal movement of the sash thus being arranged to take place about a vertical axis. The shoes 27 and 28 are of similar but opposite structure whereby corresponding parts thereof may be in opposition when the shoes of a pair are disposed in their respec-

tive guideways. As shown, the guideways 29 are provided in track members 31 of channel section fixedly mounted in the channels 22 with their flanges 32 and 33 respectively defining forwardly and rearwardly directed bearing surfaces 34 and 36 for guiding the movement of a shoe along the track. The tracks 31, it is noted, extend from one end of the channels toward, but not to, the other ends thereof.

Each of the shoes, it will now be noted, is of rectangular outline and opposite side edges 37 and 38 thereof are arranged to be disposed in opposition to the guideway bearing surfaces 34 and 36 respectively when the shoe is engaged with the track. Means are provided for urging the shoes inwardly in the guideways and against the surfaces 34 thereof, and in the present instance such means comprise flat spring members 39 having an extremity thereof protruding from the shoe edge 38 to provide a projection 41 for constant engagement against the guideway bearing surface 36 whereby the shoe is constantly urged toward the guideway surface 34. As shown, the springs 39 are generally U-shaped and are carried in grooves 42 provided in the inner surface of the shoes, and the spring projections 41 preferably lie adjacent one end of the shoe. Bearing blocks 43 are mounted on the shoe edges 37 at opposite ends thereof, such blocks preferably being of less height than are the shoes whereby their outer edges 44 provide coplanar bearing surfaces inwardly of the outer surface of the shoes for engagement beneath flanges 45 extending forwardly from the edges of the channel flanges 32 to closely overlie the blocks. In this manner, the shoe is arranged to be held against lateral removal from the guideway and the latter need extend no further from the frame webs 19 than do the shoes. As particularly shown, a shoe is formed by appropriately shaping a blank of sheet metal, the blank portion providing the rear edge 37 of the shoe being bent back upon itself to provide the blocks 43 of the shoe. The inner end of the spring 39 is also fixed to the shoe portion providing the shoe edge 37 whereby the spring is movable with the shoe, it being noted that the shoe formed as described is generally channel shaped in transverse section with the longitudinal channel thereof providing the spring groove 42.

Pivoted to the shoes 27 and 28 by means of pivot pins 46 are members 47 and 48, said members being arranged for attachment to the sash stiles adjacent the top and bottom of the sash whereby the sash is arranged for pivotal movement about an axis perpendicular to the tracks 31. Preferably, and as shown, the pivot pins 46 are disposed adjacent the same shoe ends as are the spring projections 41. The member 47, it is noted, is generally L-shaped, one arm 49 thereof being

perforated to receive the pin 46, while the other arm 51 thereof is arranged for mounting along and against the outer side of the web 24 of a side stile 23. The plate arm 51 and web 24 are provided with pairs of registering perforations for the reception of bolts for clamping the arm and web together. Preferably, the perforations 52 of the arm 51 are in the form of slots extending longitudinally of the arm whereby the pivotal axis provided is adjustably shiftable in the plane of the sash, and at least one slot of a pair is wider than need be for receiving a fastening bolt whereby said pivotal axis is also transversely shiftable with respect to the plane of the sash flanges 26. In this manner, all necessary adjustability of the relation of said pivotal axis to the sash is provided for.

The member 48, it will now be noted, is generally straight with one end thereof perforated for receiving the pivot pin 46 and the other end fixedly disposable against and beneath the web of the lower sash stile. The member 48 and the web of the lower sash stile are provided with pairs of registering perforations 56 and 57 respectively for the reception of bolts 58 by means of which the member 48 is fixed to the stile web. Means are provided for adjusting the pivotal axis provided by the member 48 in a direction transverse of the plane of the sash flanges 26, and as shown, such means comprises the formation of a perforation 56 in the form of an arcuate slot having the other perforation 56 as its axis of curvature, the degree of adjustment provided corresponding in direction and amount to the similar adjustment provided for the member 47. No other adjustment is provided for the member 48, as such will not generally be necessary.

Similarly disposed links 59 are connected between intermediate points of the top and bottom sash stiles to points of the upper and lower frame members not occupied by the tracks 31 and are pivotally connected to the webs 19 and 24 of the frame members 17 and stiles 23 respectively. The area defined by the stile webs 19, it is noted, is enough smaller than that defined within the frame flanges or casings 18 to permit the disposal of the links 59 between the frame members and sash when the latter is in its closed position, the links being appropriately mounted on brackets 61 and 62 formed to permit this disposal of the links.

It will now be noted that movement of the shoes along the tracks will variously position the sash with respect to the frame opening and that when the shoes have assumed one extreme position thereof adjacent the side frame member 63 at the end of the track 31, the sash is arranged to be in closed position. It is noted, however, that as the sash flange 64 which is arranged to come to rest in overlying relation in front of the casing 120

portion 66 provided by the member 63 moves toward the member 63 as the window is closed, its edge lies appreciably inwardly of the frame flange 18 providing the casing portion 66 and would catch therebehind if not shifted forwardly as the sash is further closed, this condition being particularly brought out in Figure 3, and means are accordingly provided for effecting such displacement of the sash as it is moved to closed position as will so dispose the flange 64 as to permit the closing of the sash. As shown, the latter means comprises the provision of one or more strikes 67 mounted on the frame member 63 and presenting oblique guide faces 70 disposed in the path of movement of the sash flange edge and terminating at the front face of the casing 63.

The displacement of the sash flange 64 out of its normal path by means of the strikes 67, it will now be noted, may only be effected if a sufficient forward movement of the shoes 27 and 28 is permitted. Yet to prevent a rattling and general looseness of the sash when in an open position, the shoes should be substantially the same width as the guideways 29 provided therefor and the necessary forward displacement thereof would not then be permitted, it being clear that such displacement need be provided for only as the fully closed position of the sash is approached. Accordingly, and as shown, a portion 68 of the bearing surface 36 of each track flange 33 adjacent the member 63 is offset forwardly to permit the necessary forward movement of the shoe against the resistance of the spring 39—as shown, this is accomplished by offsetting the track flange itself whereby the track may be formed by appropriately shaping sheet material. Preferably, and as shown, the widened track portions are of such length that the shoe ends which do not carry the pivot pins 46 never lie therein. In this manner, forward displacement of the shoes is arranged to be pivotal and about the shoe portions which remain engaged in the narrower track portion.

It will now be noted that as a shoe advances into the wider track portion it will maintain its engagement against the forwardly directed track bearing surface 32 by reason of the extension of the spring 39 to effect an engagement with the surface 68 until a strike is reached by the sash flange 64, after which the sash and shoe will be swung forwardly as described. Substantially as the flange 64 first reaches the outer surface of the casing 66, the shoe will have been swung to its most forward position, and continued closing of the sash will thereafter permit the inward movement of the shoe back toward the bearing surface 34. To insure the maintenance of a tight closing engagement of the sash flange 64 with the casing portion 66, it is desirable that the swinging

shoe end be not permitted to engage the bearing surface 34 when the sash is closed, and the permitted adjustment of the members 47 and 48 to appropriately dispose the pivotal axis of the sash thereat with respect to the plane of the flange permits a setting of the members 47 and 48 to prevent such engagement. In this manner, the springs 39 are freely operative to resiliently urge the flange 64 to maintain a seated engagement with the casing 66, it being noted that the adjacent portions of the top and bottom flanges of the sash are also resiliently held against the opposed casing portions.

To permit the movement of the sash now described, the sash flanges are appropriately notched at the top and bottom thereof, as at 69, edges 71 of the notches being engageable with the top and bottom casings 18 when the sash is reversely disposed to provide a stop for the sash. Notches 72 are provided along the front track flange 33 whereby the spring projection 41 may engage therein to hold the sash in a plurality of set open positions. At least for the lower track, notches 73 registering with the track notches 72 are provided in the opposed casing, whereby the casing channel and the shoe guideway may be drained of any water collecting therein.

In the embodiment disclosed in Figure 8, the provision of means permitting the necessary forward swinging of a sash carrying shoe, as the sash is closed, is incorporated entirely in the shoe structure. In this embodiment, like track members 81 are mounted in the channels of the top and bottom frame members 17, said tracks providing guideways 82 of uniform width. The shoes 83 are formed generally similarly to the shoes of the first described embodiment, except that the present shoes are tapered toward the pivot carrying ends thereof to permit a forward swinging of said ends about their wide ends when the sash flange 64 engages the strikes 67. When the tracks 81 and shoes 83 are used, the same operative relations between the sash 14 and frame 16 obtain as before. In the present embodiment, an outward displacement of the pivot carrying end of the shoe is, of course, permitted in all positions of the shoe, while in the first embodiment, such movement is permitted only as the sash closes.

While the mounting of my invention is here shown and described as particularly applied to mounting a sash for pivotal movement about a vertical axis, it will be clear that the same mounting may be utilized in securing a sash for pivotal movement about a horizontal axis. In the latter event, a pair of complementary members 47 might be used at opposite ends of the same sash stile for securing the sash to the shoes, it being particularly noted that the use of the member 48 at the bottom of the sash in the present

embodiment causes the weight of the sash to operate transversely of the member 48 and so does not tend to alter the adjusted mounting of the member on the bottom sash 5 stile.

I claim:

1. In a supporting means for a sash, a guideway, an elongated shoe slidably engaged with and arranged for movement 10 transversely of said guideway and having the sash pivoted thereto adjacent an end thereof, and means yieldingly urging said shoe in a reverse direction transversely of said guideway.

15 2. In a sash supporting means, a track, an elongated shoe slidably engaged with said track and having the sash pivoted thereto adjacent an end thereof, means yieldingly urging said shoe in a fixed direction transversely 20 of said track, and means arranged for a pivotal displacement of the sash engaging shoe end about the other end of the shoe oppositely of said first direction.

25 3. In a sash supporting device, means providing a guideway having opposed inner and outer guide surfaces, an elongated shoe disposed between said guide surfaces and having the sash pivoted thereto at an end thereof, means yieldingly urging said shoe 30 against one of said surfaces, and means arranged for a pivotal displacement of the sash engaging shoe-end about the other end of the shoe and away from the surface toward which said shoe is urged, said last means being arranged to be effective when the sash 35 is in a substantially closed position.

4. In a support for a sash arranged to be swung outwardly from a window frame opening and having a lateral extension for seated disposal against the front casing of the window frame, a guideway in said frame at a side of the opening, a shoe pivoted to said sash and slidably engaged in said guideway, means constantly operating to resiliently urge said shoe inwardly in the window opening, and means arranged for an outward displacement of said shoe during a seating of said sash extension against the casing.

5. In a support for a sash arranged to be swung outwardly from a window frame opening and having a lateral flange disposed parallel to its pivotal axis for seated disposal against the front casing of the window frame, means providing a guideway in said frame along a side of the opening, a shoe pivoted to said sash at the edge thereof adjacent said flange and slidably engaged in said guideway, a strike at the inner edge of said front casing engageable by said flange for directing the same outwardly of said casing when the flange is adjacent thereto, and means constantly operative to resiliently urge said shoe 60 inwardly and permitting a generally out-

ward displacement of the shoe while said flange engages said strike and casing.

6. In a support for a sash arranged to be swung outwardly from a window frame opening and having a lateral extension for seated disposal against the front casing of the window frame, a track in said frame at a side of the opening, a shoe pivoted to said sash and slidably along said track, means constantly operative to urge said shoe inwardly in the window opening, means operative against the extension to dispose the same outwardly of the front plane of the casing as the sash is closed, and means arranged for a corresponding displacement of said shoe with said extension as the sash is closed.

7. In a support for a sash arranged to be swung outwardly from a window frame opening, a guideway on said frame, a shoe slidably in said guideway and pivotally secured to said sash, and means for adjustably varying the pivotal distance of said sash from the plane of the outer face thereof.

8. In a support for a sash arranged to be swung outwardly from a window frame opening and having an edge portion for seated disposal against the front casing of the window frame, a guideway at a side of the window opening, a shoe pivoted to said sash and slidably engaged with said guideway, and means for adjustably varying the distance between the pivotal axis of said sash and a plane of the sash.

9. In a support for a sash arranged to be swung outwardly from a window frame opening and having a lateral flange for seated engagement against the front casing of the window frame, a guideway at a side of the window opening, a shoe slidably engaged in said guideway, a member carried by said sash and pivotally connected to said shoe for pivotal movement about an axis parallel to the plane of the sash, and means adjustably fixing said member to said sash whereby the distance between the pivotal axis of the shaft and said plane may be varied.

10. In a support for a sash arranged to be swung outwardly from a window frame opening and having a lateral flange for seated disposal against the front of the window frame when the sash is in closed position, means operative to resiliently hold said flange against the front of the window frame when the sash is in said closed position.

11. In a mounting for a sash arranged to be swung between various positions thereof with respect to a window frame opening and having a lateral extension for disposal in front of the window frame, said extension being arranged to be disposed at least partially behind the plane of said frame front when said sash is in opened position, means operative against said extension to dispose it outwardly of said plane as the sash is closed

to thereby permit the disposal of the sash in closed position.

12. In a sash supporting device, means providing a guideway having parallelly related and oppositely directed guide surfaces, a shoe slidably engaged with said guideway surfaces and arranged for pivotal connection to the sash, means resiliently maintaining an edge of said shoe against one of said surfaces while said sash is in open position, means operative by and upon a closing of the sash to at least partially space said shoe edge from said surface.

13. In a support for a sash arranged to be swung outwardly from a window frame opening, a guideway on said frame, a shoe slideable in said guideway, a member carried by said sash and pivoted to said shoe, and means securing said member to said shoe whereby the pivotal distance of said sash from the plane of the outer face thereof may be adjustably varied.

In testimony whereof, I have hereunto set my hand at Oakland, California, this 19th day of May, 1928.

JAMES ADAMS STEWART.
